UNITED STATES PATENT OFFICE.

EUGENE F. BEEBE, OF MINNEAPOLIS, MINNESOTA.

WRINGER.

Application filed February 23, 1921. Serial No. 447,129.

To all whom it may concern:

Be it known that I, EUGENE F. BEEBE, a citizen of the United States, residing at Minneapolis, in the county of Hennepin and State of Minnesota, have invented certain new and useful Improvements in Wringers; and I do hereby declare the following to be a full, clear, and exact description of the invention, such as will enable others skilled in the art to which it appertains to make and use the same.

My invention relates to improvements in clothes wringers of the type disclosed and broadly claimed in my two U. S. pending applications entitled "Wringers", one of which was filed June 1, 1920, under Serial Number 385,658, and the other of which was filed February 7, 1921, under Serial Number 443,181, and has for its object to improve the same in the several particulars hereinafter noted.

To the above end, the invention consists of the novel devices and combinations of devices hereinafter described and defined in the claims.

In the accompanying drawings, which illustrate the invention, like characters indicate like parts throughout the several views.

Referring to the drawings:

Fig. 1 is a view partly in side elevation and partly in central vertical section, with some parts broken away;

Fig. 2 is a view partly in bottom plan and partly in horizontal section taken on the line 2-2 of Fig. 1;

Fig. 3 is a fragmentary detail view in plan showing the upper left-hand portion of the wringer;

Fig. 4 is a fragmentary detail view partly in plan and partly in horizontal section taken on the line 4-4 of Fig. 1; and

Fig. 5 is a perspective view of one of the plungers and a portion of the combined rocking and releasing bar on an enlarged scale, some parts being indicated by means of broken lines.

The wringer frame illustrated is of the type shown in my co-pending application S. N. 385,658, heretofore identified, but may be of the type disclosed in my later application and includes a pair of laterally spaced uprights 6 having bifurcated upper ends in which is secured a top tie-bar 7, the ends of which project outward of said uprights. Co-operating upper and lower pres-

sure rolls 8 and 9, respectively, are provided with shafts 10 and 11, respectively, the former of which shafts is journaled in floating bearings 12 mounted between the prongs 60 of the uprights 6, and the latter of which is journaled in fixed bearings 13 removably mounted between said prongs.

Loosely journaled on the left-hand end of the shaft 11 is a bevel gear 14 having 65 in its hub lugs 15 adapted to enter notches 16 in a sliding clutch 17 mounted on said shaft and held for rotation therewith by a pin and slot 18. Also loosely mounted on the shaft 11, inward of the clutch 17, 70 is a collar 19 having, on its outer end, an outstanding flange 20. The clutch 17 is also provided, at its inner end, with an outstanding flange 21 and a coiled spring 22, encircling the shaft 11, is compressed between 75 the clutch 17 and collar 19 and is under strain to yieldingly hold the clutch 17 interlocked with the gear 14 to connect the same to the shaft 11. The gear 14 may be driven by any suitable driving mechanism 80 not shown. Shifting mechanism for the clutch 17 includes a vertically disposed lever 23 intermediately pivoted to a bracket 24 secured to the adjacent frame upright 6 and has, at its lower end, a fork 85 25 to receive, between the prongs thereof, the two outstanding flanges 20 and 21 and hold the collar 19 as a base of resistance for the spring 22 and move the clutch 17 against the tension of said spring to release 90 the same from the gear 14. The pressure roll 8 is driven from the pressure roll 9 by intermeshing gears 26.

Pressure devices for the upper roll 8 include coiled springs 27 seated in spring 95 pockets 28 carried by sliding blocks 29 cast integral therewith and supported on the floating bearings 12. Flanges 30, on the sliding bearings 29, engage opposite faces of the uprights 6 and guide said bearings 100 for floating movement with the bearings 12. The pressure devices also include plungers 31 having, on their lower ends, spring caps 32 which rest on the springs 27 and work within the spring pockets 28. On the upper 105 ends of the plungers 31 are cylindrical heads 33, which are free to move endwise in cylindrical seats 34 formed in the projecting ends of the top tie-bar 7. The plungers 31 are held against rotation, but 110 with freedom for endwise sliding movement in the seats 34 by forming on the

sides thereof diametrically opposite vertically elongated lugs 35 which work in slots 36 formed in the sides of said seats, as best shown in Fig. 3. The heads 33 of the 5 plungers, seats 34 and slots 36 are covered by caps 37 secured to said heads by screws.

To render the pressure devices operative or inoperative, I provide a combined locking and releasing bar 38 mounted on the 10 under face of the top tie-bar 7 for endwise sliding movement and held in position by screws 39 which extend through slots 40 in said bar and have screw-threaded engagement with the top tie-bar 7. The bar 38 is 15 provided with apertures 41, on the sides of which are pairs of depending and longitudinally extended cams 42 arranged to engage diametrically opposite lugs 43 formed with the plunger heads 33 and aligned with the 20 lugs 35. When the bar 38 is moved to its extreme right-hand position, the apertures 41 are of such size as to permit the plunger heads 33 and the lugs 35 and 43 to move freely therein. A left-hand movement of 25 the bar 38 will carry the cams 42 onto the lugs 43, depress the plungers 31, which compress the springs 27 and thereby apply pressure to the rolls. As shown, the cams 42 are formed by pressing the same directly 30 from the bar 38, but, of course, may be formed in any other suitable way.

Endwise movement is imparted to the bar 38 to place the pressure devices under tension and release the same by a lever 44 preferably intermediately pivoted, as shown, to a bearing 45 secured to the upper face of the top tie-bar 7 and having a depending arm 46 which works in a slot formed in said tie-bar and extends through a seat 47 formed 40 in the bar 38 to connect the lever 44 thereto. The lever 44, as shown, is in the form of a rocker and extends longitudinally in respect to the bar 7 and its two extreme movements are limited by engagement of its 45 outer ends with the upper face of the tie-bar 7. The clutch 17 is simultaneously operated during the movement of the bar 38 by extending the upper end thereof into a seat 48 formed in the overlying portion of the bar 38.

Yoke-like guards 49, for the gears 26 and the ends of the rolls 8 and 9, are suspended by studs 50 from the sliding blocks 29. A drain board 51 is pivoted to the uprights 55 6 for movement from one side of the frame to the other.

The operation of the improved wringer may be briefly described as follows:

In the drawings, the wringer is shown 60 adjusted for work and, in which adjustment, the right-hand end of the lever 44 is depressed, which holds the bar 38 in its extreme left-hand position with its cams 42 in engagement with the lugs 43 and thereby 65 locks the pressure devices under tension with

the upper roll 8 pressed onto the lower roll 9. When the lever 44 is in this position, the bar 38 also holds the clutch-shifting lever 23 in a position in which the clutch 17 is held by the spring 22 interlocked with the gear 14 to connect said gear to the shaft 11, to drive the same, and which shaft 11, in turn, drives the shaft 10 to the gears 26.

In case the operator's hand is caught in the clothes being fed to the wringer and is being drawn thereby to the pressure rolls, or in case his hand is actually caught between the rolls, he may instantly release the pressure on the rolls and stop the driving power to the rolls by striking the raised or left-hand end of the lever 44 to depress the same. This movement of the lever 44 will move the bar 38 to the right and thereby withdraw the cams 42 from the lug 43, which releases the plungers 31 and permits the same to move upward in their seats 36 and the apertures 41 in said bar under the action of the springs 27, which, in turn, releases the pressure on the upper roll 8. The movement of the bar 38 to the right also 90 rocks the lever 23, which, by its fork engagement with the flanges 20 and 21, shifts the clutch 17 and collar 19 axially on the shaft 11 and withdraws said clutch from the gear 14 and thereby stops the driving power to 95 said shaft.

To again put the rolls under pressure and start the driving action to the shaft 11, the operator, by striking the right-hand or raised end of the lever 44, moves the bar 100 38 to the left, which causes the cams 42 to engage the lugs 43 and thereby depresses the plungers 31 and places the springs 27 under tension. This movement of the bar 38 to the left also rocks the lever 23 to release the clutch 17 and allow the same to connect the gear 14 to the shaft 11. In case the notches 16 on the clutch 17 do not instantly mesh with the lugs 15 on the hub of the gear 14 at the time the pressure devices are placed under tension, the movement of the lever 23 will slide the collar 19, by the engagement of one of the prongs of its form 25 with the flange 20, bodily toward the clutch 17 and thereby compress 110 the spring 22 between said collar and clutch. The other prong of the fork 25 will move away from the clutch flange 21 and, as soon as the gear 14 has moved far enough to bring its lugs 15 into alignment with the notches 16, the compressed spring 22 will slide the clutch 17 on the shaft 11 and thereby cause the same to interlock with the gear 14 and connect the same to the shaft 11.

After the operator has finished his work 125 with the improved wringer, it is only necessary to depress the raised left-hand end of the lever 44 by striking the same to release the pressure on the rolls and thereby increase the life thereof. This same movement also 130

disconnects the driving mechanism from the rolls. The next time the wringer is to be used, pressure may be instantly applied to the rolls and the driving mechanism connected thereto by depressing the raised right-hand end of the lever 44.

What I claim is:—

1. The combination with co-operating pressure rolls, of means for driving one of the rolls including a yielding set clutch, pressure devices for the rolls, an endwise movable combined locking and releasing bar for the pressure devices, and a clutch-releasing lever directly and loosely connected to said bar and arranged, when said bar is moved into one position, to release the clutch and, when moved into another position, to permit independent setting of the clutch.

2. The combination with a frame having a top bar, of co-operating pressure rolls, pressure springs operative on one of the rolls, plungers operative on the springs to place the same under tension and for releasing the same, seats in the top bar in which the plungers are mounted for endwise movement, an endwise movable bar having apertures through which said plungers work and operative on the plungers to depress the same and place the springs under tension and for releasing the same, and caps on the plungers for closing the seats in the top bar when the plungers are depressed.

3. The combination with co-operating pressure rolls, of means for driving one of the rolls including a clutch, pressure devices including springs operative on one of the rolls, a bar having cams operative on the pressure devices for placing the same under tension and for releasing the same, means operative on the bar to move the same into one position to place the pressure devices under tension and into another position to release the same, and clutch operating mechanism including a yielding element arranged to be operated by said bar and permitting the movement of said bar to place the pressure devices under tension irrespective of the position of the clutch and operative subsequently to throw the clutch into driving action and to render said clutch inoperative when the bar is moved to release the pressure devices.

4. The combination with co-operating pressure rolls, of pressure devices operative on one of the rolls, an endwise movable combined locking and releasing bar for setting the pressure devices and for releasing the same, and an intermediately pivoted lever connected to said bar and arranged, when one of its ends is depressed, to move said bar and thereby render the pressure devices operative and, when its other end is depressed, to move said bar and thereby render the pressure devices inoperative.

5. The combination with co-operating pressure rolls, of pressure springs operative on one of the rolls, plungers operative on the springs and having lock lugs, an endwise movable bar having cams operative on said lugs, and means for moving the bar into one position to carry its cams onto the said lugs to depress the plungers and place said springs under tension and movable into another position to release the plungers.

6. The combination with co-operating pressure rolls, of springs operative on one of the rolls, plungers operative on the springs and having diametrically opposite lock lugs, an endwise movable bar having apertures through which the plungers work and also having cams operative on the lugs, means for moving the bar into one position to carry its cams onto said lugs and depress the plungers and place the springs under tension and for moving the same into another position to release the plungers.

7. The combination with a frame having a top bar, of co-operating pressure rolls, pressure springs operative on one of the rolls, plungers operative on the springs to place the same under tension and for releasing the same, an endwise movable bar operative on the plungers to depress the same and place the springs under tension and for releasing the same, a horizontally disposed lever intermediately pivoted to the top bar and having a depending arm connected to the bar, said lever being arranged so that when one of the ends is depressed it will move the bar to depress the plunger and when the other end thereof is depressed it will move the bar to release the plungers.

In testimony whereof I affix my signature.

EUGENE F. BEEBE.
